[57] **CLAIM**

The ornamental design for a utility body insert, as shown and described.

DESCRIPTION

FIG. 1 is a perspective view of utility body insert showing my new design;
FIG. 2 is a right side view thereof;
FIG. 3 is a back end view thereof;
FIG. 4 is a left side view thereof;
FIG. 5 is a top view thereof;
FIG. 6 is a bottom view thereof;
FIG. 7 is a front end view thereof;
FIG. 8 is a perspective view of a utility body insert showing an alternative embodiment of my new design;
FIG. 9 is a right side view thereof;
FIG. 10 is a back end view thereof;
FIG. 11 is a left side view thereof;
FIG. 12 is a top view thereof;
FIG. 13 is a front end view thereof;
FIG. 14 is a perspective view of a utility body insert showing another alternative embodiment of my new design;
FIG. 15 is a back end view thereof;
FIG. 16 is a top view thereof;
FIG. 17 is a front end view thereof; and,
FIG. 18 is a bottom view thereof.
